Inventor:

Andrew St Blunk

UNITED STATES PATENT OFFICE.

ANDREW F. BLUNK, OF INDIANAPOLIS, INDIANA.

STRAW-CUTTER.

Specification of Letters Patent No. 25,378, dated September 18, 1859.

To all whom it may concern:

Be it known that I, ANDREW F. BLUNK, of Indianapolis, county of Marion, and State of Indiana, have invented a new and 5 useful Improvement in Straw-Cutters; and I hereby declare the following to be a full and exact description of the same, reference being had to the accompanying drawings and the letters of reference marked thereon, 10 like letters referring to like parts.

Figure 1, is a side elevation; and Fig. 2, is a section of the machine.

A, is the frame supporting the box proper, and the effective machinery.

15 E, is the knife wheel—performing also the function of a balance wheel in equalizing the power put forth by the operator.

K, K, are elbow shaped arms of the knife wheel; and each arm carries T, T, the knives, 20 which cut the straw, the whole of these attached to the shaft—F,—upon which is the wheel G, gearing with pinion H, which is upon the shaft of the roller C, operating the endless belt I, which passes around the rollers C, and D.

Upon the rollers D, B, are attached the pulleys J, J, represented by the dotted lines, which give motion to the roller B, by the pulley cord N. The roller B, is designed to 30 force the straw between the rollers C, B.

Upon the inside of the box M, are the slides S, S,—to the bottom of which are attached the spiral springs O, O. In these slides are the journals of the roller B,—by 35 which arrangement the pressure of the roller B, is equalized upon the straw as it passes toward the knives.

P, P, are adjustable, and, gaged slides supporting the roller D,—and by means of 40 which the tension of the endless belt I, I, can

be regulated to suit any emergency—by set screws Q, Q.

The operation of the machine is simply as follows, viz: Place the straw upon the endless belt I, I,—when, by turning the wheel 45 E, which carries the knives upon its arms, (four or more,) the endless belt is set in motion, and carries the straw up to the knives, between the rollers; and, the straw being thus compressed by passing between 50 the rollers, is cut with a very slight expenditure of power in the operator, these knives having an elbow shape on their backs, and an angular concavity at their edge, and so adjusted that when they sweep past the face 55 of the box they cut with a drawing motion—in close imitation of the motion in the common hand cutting box, having but a single knife. L, is the point at which the cutting is done. This elbow shaped knife has advantages over all other knives, placed in a rotary wheel, and accomplishes something 60 not done by any other similar machine—a complete drawing cut.

Having thus fully described my invention, what I claim as new, and desire to secure by Letters Patent, is,

A straw cutter constructed as herein shown and specified:—that is to say—with angular knives T;—arms K;—wheel E;—feed rollers B, C, and D;—slides P, S;—springs O;—band N;—pulleys J, J;—and endless belt I,—when these several parts are constructed and arranged for operation conjointly, as, and for the purposes described.

ANDREW F. BLUNK.
